CLAIM

The ornamental design for a knee brace, as shown and described.

DESCRIPTION

FIG. 1 is a front, right and bottom perspective view of a knee brace, showing our new design;

FIG. 2 is a front, right and bottom perspective view of a knee brace shown with the rectangular feature removed for clarity of disclosure;

FIG. 3 is a rear, left and top perspective view thereof;

FIG. 4 is a front view thereof;

FIG. 5 is a rear view thereof;

FIG. 6 is a left side view thereof;

FIG. 7 is a right side view thereof;

FIG. 8 is a top plan view thereof;

FIG. 9 is a bottom plan view thereof; and

FIG. 10 is a front, right and bottom perspective view of the rectangular feature shown removed from the knee brace for clarity of disclosure ;

FIG. 11 is a rear, left and top perspective view thereof;

FIG. 12 is a front view thereof;

FIG. 13 is a rear view thereof;

FIG. 14 is a left side view thereof;

FIG. 15 is a right side view thereof;

FIG. 16 is a top plan view thereof;

FIG. 17 is a bottom plan view thereof; and,

FIG. 18 is an enlarged view of portion of 18 of FIG. 2.

The broken lines shown in the drawings illustrate portions of the knee brace that form no part of the claimed design.
